UNITED STATES PATENT OFFICE

159,026 FOLDABLE CLOTHES RACK

Arnold Wegner, New York, N. Y.; Hans Manfred Wegner, administrator of said Arnold Wegner, deceased

Application December 11, 1948, Serial No. 150,111

Term of patent 7 years

(Cl. D33—8)

To all whom it may concern:

Be it known, that I, Arnold Wegner a citizen of the United States, residing at New York, in the county of New York and State of New York, have invented a new, original, and ornamental Design for a Foldable Clothes Rack, of which the following is a specification, reference being had to the accompanying drawing, forming part thereof.

In the drawing:

Fig. 1 is a perspective view of the foldable clothes rack showing my new design in closed position.

Fig. 2 is a perspective view of the foldable clothes rack showing my new design with the arms in their extended, open position.

Fig. 3 is a horizontal sectional view on lines 3—3 of Fig. 2.

I claim:

The ornamental design for a foldable clothes rack, as shown.

ARNOLD WEGNER.
